UNITED STATES PATENT OFFICE.

CHARLES M. WHITMORE, OF MERIDEN, CONNECTICUT.

DESIGN FOR A SPRING.

SPECIFICATION forming part of Design No. 25,237, dated March 10, 1896.

Application filed January 27, 1896. Serial No. 577,068. Term of patent 14 years.

To all whom it may concern:

Be it known that I, CHARLES M. WHITMORE, a citizen of the United States, residing at Meriden, in the county of New Haven and 5 State of Connecticut, have invented and produced a new and original Design for a Spring, of which the following is a specification, reference being had to the accompanying drawings, in which—

10 Figure 1 is a perspective view of a spring, showing my design. Fig. 2 is a front elevation. Fig. 3 is a plan view, and Fig. 4 is a side elevation thereof.

15 My spring is a two-armed plate-spring, the arms standing at an acute angle to each other.

A is the arm which constitutes the shank of the spring, and B is the other arm, which constitutes the body of the spring. These arms

stand at an acute angle to each other and join each other with a short and graceful curve at 20 5. The outer ends of both arms are slightly rounded, as shown, and the outer end of the arm B is curved outwardly, so as to form a convex face 6 on its inner side and a concave portion 7 on its outer side, as shown. The shank 25 A is also perforated near its end, the perforation being preferably in the form of an oblong hole 8, the longest dimensions of said hole extending longitudinally with said shank.

What I claim is—

30 The design for a spring, substantially as shown and described.

CHARLES M. WHITMORE.
